SPRING HINGE.

(Application filed June 21, 1900.)

(No Model.)

2 Sheets—Sheet 2.

UNITED STATES PATENT OFFICE.

MARTIN C. BERSTED, OF CHICAGO, ILLINOIS.

SPRING-HINGE.

SPECIFICATION forming part of Letters Patent No. 691,838, dated January 28, 1902.

Application filed June 21, 1900. Serial No. 21,041. (No model.)

To all whom it may concern:

Be it known that I, MARTIN C. BERSTED, a citizen of the United States, residing at Chicago, in the county of Cook and State of Illinois, have invented certain new and useful Improvements in Spring-Hinges, of which the following is a full, clear, and exact specification.

My invention relates to spring-hinges generally, but more particularly to that class of spring-hinges employed for swinging doors or doors which open in both directions; and it has for its primary object to provide an improved construction of hinge which may be embedded in the floor or any other convenient surface and connected with the edge of the door in such a manner as to at once serve the twofold purpose of a hinge or pivot for the door and a spring for returning the door to its normal position with reference to the door jamb or casing.

Another object of my invention is to provide improved means for varying the normal position or angularity of the door with relation to the spring and independently of the spring, so that should the door fail to accurately register with the door-jamb or with the edge of the companion door it may be adjusted without increasing or decreasing the tension of the spring until it is in the correct position.

A still further object of my invention is to provide means for hinging the upper end of the door which will avoid the excessive wear due to the lateral strain of the door against the pintle of the hinge, thereby enabling the door to swing more freely and preventing it from sagging out of alinement with the door-jamb or with the companion door.

With these ends in view my invention consists in certain features of novelty in the construction, combination, and arrangement of parts by which the said objects and certain other objects hereinafter appearing are attained, all as fully described with reference to the accompanying drawings and more particularly pointed out in the claims.

In the said drawings, Figure 1 is an elevation of a door provided with my improvement. Fig. 2 is an enlarged detail vertical sectional view of the upper edge or end of the door and a part of the jamb, showing the improved means for hinging the upper end of

the door. Fig. 3 is a section thereof taken on the line 3 3, Fig. 2. Fig. 4 is an enlarged vertical sectional view of the lower corner of the door and my improved spring mechanism socketed in the floor. Fig. 5 is a detail sectional view of the spring mechanism, showing certain interior parts in elevation. Fig. 6 is a similar view looking at right angles to the device as it appears in Fig. 5. Fig. 7 is a transverse section taken on the line 7 7, Fig. 5. Fig. 8 is a transverse section taken on the line 8 8, Fig. 5. Fig. 9 is a detail transverse section taken on the line 9 9, Fig. 4. Fig. 10 is a plan view of a blank from which the sleeve hereinafter described is formed. Fig. 10^a is an edge view thereof. Fig. 11 is a perspective view of said sleeve. Fig. 12 is a horizontal sectional view taken on the line 12 12, Fig. 1, showing the means for adjusting the door; and Fig. 13 is a rear edge elevation thereof.

1 represents the swinging door, and 2 a door-jamb, to the upper edge of which the door may be hinged in any suitable manner, 75 but preferably by means of a pintle 3, which is formed on a plate 4, secured to the door by screws 5 or other suitable means, and which pintle 3 projects upwardly into a socket or cup 6, formed on a similar plate 7, secured 80 to the jamb of the door by screws 8. The pintle 3 is provided with an annular ball groove or race in which are arranged a number of balls 9, which are held in place by and bear against the sides of the sleeve 6, so that 85 the lateral strain or tendency of the door to sag will be borne by the balls 9 and the wear on the pintle 3 thus reduced to the minimum. The sleeve 6 is socketed in the jamb, and the pintle 3 is held from pulling downwardly out 90 of the socket 6 by means of a cap 10, which overlaps the end of the sleeve 6 and is secured to the pintle 3 by screw 11 or other suitable device.

The lower edge of the door, at a point in 95 axial alinement with the pintle 3, is hinged or supported upon a spindle 12, having a projecting upper end 12^a and which projects downwardly into a floor socket or casing 13, embedded in the floor and having a lateral 100 flange 14 surrounding its upper edge, which may also be embedded in the floor flush therewith and held in place by means of screws 15 or other suitable devices. This socket 13

forms a housing for the spring mechanism which I shall presently describe, and the top of the socket is closed by a cap-plate 16, whose outer edges are also preferably flush 5 with the floor, but whose upper face is convexed, as clearly shown in Figs. 4, 5, and 6, so that water and dirt will be prevented from entering the socket 13. The cap-plate 16 is recessed in the flange 14, as shown in said 10 Figs. 4, 5, and 6, and secured thereto by screws or other suitable devices 17.

The socket 13, which is preferably formed of sheet metal pressed or stamped in the desired shaped, is provided in its bottom with 15 a pivot 18, formed by drawing up the metal, as clearly shown in Fig. 4, and the lower end of the spindle 12 is formed with a cup 19, which fits over the pivot 18 and rests upon a series of antifriction-balls 20, interposed in 20 a suitable race 21, formed around the upper edge of the pivot 18. By this means the spindle 12 is journaled at its lower end, and being fixed to the door at its upper end and in axial alinement with the pintle 3 it will 25 be held in its proper vertical position during the rotation of the door upon its hinges, which are constituted by the spindle 12 and the pintle 3.

Secured to or formed on the spindle 12 is 30 a flange 22, which is provided on its upper side with a lug 23 and on its lower side with a lug 24. This flange and said lugs are preferably formed by means of two disks, each of which has one of the lugs 23 24 struck up 35 on the edge thereof, and after which the disks are pushed together back to back on the spindle 12 and held by lugs 25, serving as keys, or other suitable devices, with the edge of one lug 23 preferably in line with the edge of 40 the other lug 24, as better shown in Fig. 6, the lugs 25 being bent into the keyways 12^b in the spindle, as shown in Fig. 9.

Surrounding the spindle 12 at a point below the flange 22 is a collar 26, which is provided on its upper edge with a lower lug 27, adapted to be engaged by the lug 24 on the flange 22, and is also formed with an enlarged lateral flange 28, on the bottom of which is formed or secured a pendent lug 29, arranged 50 to engage with a stop or lug 30, formed in the bottom of the socket 13, preferably by drawing up the metal, as shown in the drawings, the collar 26 being held from settling to the bottom of the socket 13 by the flange 28, resting 55 on the lug 30.

Arranged over and resting upon the flange 22 is a sleeve 31, which fits around the spindle 12 and is provided at its lower end with a laterally-extending lug 32, arranged in line 60 with and adapted to be engaged by the upper lug 23 on the flange 22, and inserted over and journaled on the sleeve 31 is a second upper collar 33, whose lower end is provided with an enlarged flange 34, like the flange 65 28, and these two flanges 28 34 are provided with peripheral notches 35 36, respectively, for the engagement of the upper and lower

ends of a coil-spring 37, a plurality of said notches being employed merely for the purpose of convenience in finding a proper adjustment for the spring. The upper end of the upper collar 33 is provided with a series of teeth 38, as better shown in Figs. 5 and 6, which engage with a corresponding series of teeth on a ring 39, slipped over the upper end 70 of the sleeve 31, and secured to the sleeve so as to revolve therewith by means of one or more pins 40, which pass through the ring 39 and engage in vertical openings 41, formed in the sleeve 31, whereby the ring 39 may be 80 moved longitudinally of the sleeve 31 for causing its teeth to disengage the teeth 38, but will be compelled to rotate with the sleeve 31 and to impart the motion of said sleeve to the upper collar 33, and consequently to the 85 upper end of the spring 37. The sleeve 31, at a point just above the flange 34, is provided with a second lug 42, which is adapted to engage with a stop or lug 43, formed on or secured to the bottom of the cap-plate 16 for 90 limiting the rotation of the sleeve 31 in one direction, and consequently limiting the rotation of the upper collar 33 in that direction, the stop 30 being adapted to limit the rotation of the lower collar 26 in the opposite direction. For convenience in putting the members of the device together the flange 34 is provided with an aperture 44, so that the flange 34 may be passed downwardly over the lug 42 on the sleeve 31, the flange of the upper collar 33 being located at a point between the lugs 32 42 on the sleeve 31. 95

The purpose of the toothed connection between the upper collar 33 and the ring 39, connected with the sleeve 31, is to provide 100 for varying the tension of the spring 37, which may be accomplished by raising the toothed ring 39 out of engagement with the teeth 38 of the upper collar 33, and then turning the upper collar 33 on the sleeve 31 in the proper 105 direction by means of any suitable key or a nail inserted in any one of a number of sockets 45 in the upper collar 33 until the desired tension is attained, whereupon the toothed ring 39 may be let down into engagement 110 with the teeth 38 for holding the parts at the proper adjustment, the ring 39, if desired, being also provided with one or more sockets 46 for the insertion of a pin to facilitate lifting the ring out of engagement with the teeth 38. 115 120

In order that the spring 37 may retain its form and be prevented from unduly twisting at its mid-length, I locate within the same a barrel 47, which is of sufficient length to project from one of the flanges 28 34 to the other 125 and surrounds the flange 22. At its mid-length it may be slightly reduced in diameter, as shown at 48, so as to permit the intermediate convolutions of the spring to contract. The projecting upperend of the spindle 130 12 is flattened on one side, as shown at 12^a, and secured in a socket-piece 49, arranged on the lower edge of the door, as will be hereinafter more fully described, and the upperend of the

upper collar 33 projects through the cap-plate 16, the lug 42 at the upper end of the sleeve 31 being located just below the cap-plate 16, so as to engage with the stop 43 thereon, and 5 the upper collar 33 is provided with a peripheral slot 50, formed throughout about two-thirds of its circumference for permitting the lug 42 to revolve with the sleeve 31, or, in other words, to permit the upper collar 33 to 10 be revolved with reference to the lug 42 when taking up the tension of the spring, the lug 42 at other times during the operation of the device maintaining a fixed relation to the upper collar 33. With this construction it will 15 be seen that the normal tension of the spring will hold the lug 42 against the stop 43 at the top of the socket 13 and the lug 29 against the stop 30 at the bottom of said socket, and when the door is opened, resulting in turning the 20 spindle 12, the lug 23 on the spindle 12 will push the lug 32 on the sleeve 31 toward the left and contract the spring, moving the lug 42 away from the stop 43. When the door is released, the spring will return the parts to 25 their normal position, and the momentum of the door will carry the spindle 12 backward past its normal position, causing the lug 24 thereon to push the lug 27 on the lower collar 26 toward the right and in doing so contract the lower end of the spring. When the 30 momentum of the door is overcome by the spring, the spring returns the parts to their normal position, (shown in Fig. 6,) with the lug 29 resting against the stop 30.

35 In Figs. 10 and 11 of the drawings I have shown a blank for the production of the sleeve 31 with its lugs 32 42 formed thereon and the openings 41 for the pins 40 formed in the end thereof. This blank, as clearly shown in Fig. 40, consists of a sheet of metal or other suitable material 51, upon the lower edge of which is formed a tongue or projection 52, in the upper edge of which are formed two openings 53, while at one end a tongue 54 is struck 45 out and turned down at right angles to the plane of the plate 51, as shown in Fig. 10. In converting this blank into the sleeve shown in perspective in Fig. 11 the plate 51 is curved around to form a cylinder, the projection 52 is turned outwardly at an angle to the face of the plate 51 to form the bottom lug 32, the tongue 54 constituting the upper lug 42, and the opening 55 formed by bending out the tongue 54 is closed by a tongue 56, 50 formed on the opposite end of the plate 51. The openings 53 are arranged at such distance apart as to come diametrically opposite each other when the plate 51 is bent into a cylindrical form, so that they constitute the 55 openings 41 in the upper end of the sleeve, the cylindrical part of the plate 51 constituting the sleeve proper.

55 The socket-piece 49 is provided with a socket 57, which is complementary in shape to the beveled end 12° of the spindle 12, and is adapted to support the door upon said spindle and at the same time cause the spindle to rotate

against the inertia of the spring when the door is opened. This socket-piece 49 has pivotal connection with the door at a point eccentric 7c to the spindle 12, and consequently the door is virtually pivotally supported on the spindle 12 on an axis eccentric to the axis of said spindle. The purpose of this is to enable the angularity of the door to be altered with reference to the spring or to the spindle 12 when in normal position, thus providing means for adjusting the door with reference to its companion door or to the jamb independently of the spring. The specific mechanism for accomplishing this consists of the socket-piece 49, which is pivoted on the upper side of a flange 58 formed on the lower edge of a plate 59, which is secured to the side of the door, the flange 58 projecting under the edge of the 85 door, so as to hold the socket-piece 49 between the flange and the door. 60 is the pivot on which the socket-piece 49 turns and which is riveted or otherwise secured in the flange 58. The flange 58 is provided at each end with a 90 turned-up boss 61, and in each end of the socket-piece 49 is threaded a set-screw 62, one end of each of which is adapted to abut against one of the bosses 61, while the other end is arranged opposite a hole 63 in the plate 59, so 95 as to be accessible by a screw-driver or other device for turning the screw 62, and thereby turning the socket-piece 49 on its pivot 60, one of the screws 62 being turned out while the other is turned in. The socket-piece 49 100 is also held and rendered more rigid by screws 64 passing through a plate 65 secured to the opposite side of the door to that on which the plate 59 is located and threaded in the socket-piece 49, as clearly shown in Fig. 12. 105

Having thus described my invention, what I claim as new therein, and desire to secure by Letters Patent, is—

1. The combination of a casing having lower and upper stops, a spindle pivoted in the casing, a flange having upper and lower lugs and secured to the spindle, a lower collar fitting around the spindle having an upper lug so arranged as to be engaged by the lower lug of the flange, and a lower lug so arranged as to engage with the lower stop of the casing, a sleeve fitting around the spindle above the flange thereof having a lower lug so arranged as to be engaged by the upper lug of the flange, and an upper lug so arranged as to engage with the upper stop of the casing, an upper collar fitting around the sleeve and connected therewith, a coil-spring surrounding the spindle and having one end secured to the lower collar and its other end secured to the upper collar, and a barrel slightly reduced at its mid-length, fitted between the collars and located between the spindle and the spring for sustaining the latter. 115
2. The combination of a casing having lower and upper stops, a spindle pivoted in the casing, having longitudinal keyways, a flange composed of two disks, each having a lug struck up from the edge thereof, arranged 120
3. The combination of a casing having lower and upper stops, a spindle pivoted in the casing, having longitudinal keyways, a flange composed of two disks, each having a lug struck up from the edge thereof, arranged 125
4. The combination of a casing having lower and upper stops, a spindle pivoted in the casing, having longitudinal keyways, a flange composed of two disks, each having a lug struck up from the edge thereof, arranged 130

back to back and formed with key-lugs bent into the keyways, a lower collar fitting around the spindle having an upper lug so arranged as to be engaged by the lower lug of the flange, 5 and a lower lug so arranged as to engage with the lower stop of the casing, a sleeve fitting around the spindle above the flange thereof having a lower lug so arranged as to be engaged by the upper lug of the flange, and an 10 upper lug so arranged as to engage with the upper stop of the casing, an upper collar fitting around the sleeve connected therewith, and a coil-spring surrounding the spindle having one end secured to the lower collar 15 and its other end secured to the upper collar.

3. The combination of a casing having lower and upper stops, a spindle pivoted in the casing, a flange having upper and lower lugs and secured to the spindle, a lower collar fitting 20 around the spindle, having a lateral flange provided with an upper lug so arranged as to be engaged by the lower lug of the spindle-flange, and a lower lug so arranged as to engage with the lower stop of the casing, a 25 sleeve formed with vertical openings and fitting around the spindle, above the spindle-flange and having a lower lug so arranged as to be engaged by the upper lug of the spindle-flange, and an upper lug so arranged as 30 to engage with the upper stop of the casing, an upper collar, fitting around the sleeve, having a lateral flange, and series of teeth on its upper end, a ring having a series of teeth mesh-

ing with the teeth on the upper collar, pins connecting the ring with the vertical openings in 35 the sleeve, and a coil-spring surrounding the spindle having one end secured to the lower collar and its other end secured to the upper collar.

4. A sleeve-blank formed integral with a 40 lower tongue, with openings in its upper edge, a tongue severed from one end of the blank to provide an opening and a tongue at the other end of the blank adapted to close the end opening. 45

5. A sleeve formed integral from a blank, with a lower outwardly-projecting tongue, an upper outwardly-projecting tongue providing an opening and a tongue closing the opening over the upper tongue. 50

6. The combination of a door and its frame of a pivot-hinge comprising in its construction a plate formed with an integral pivot-pin having an annular ball-groove and adapted to be secured to the upper edge of the door, a 55 plate formed with an integral cup into which the pivot-pin projects, and adapted to be seated in a socket in the under side of the lintel of the door-frame, antifriction-balls located in said annular groove a cap overlapping said cup, and means for securing the cap to the pivot-pin, substantially as described. 60
